UNITED STATES PATENT OFFICE

170,975

RADIATOR FLOW TEST MACHINE

James V. Grasso, Omaha, Nebr., assignor to Inland Manufacturing Company, Omaha, Nebr., a corporation of Nebraska

Application October 18, 1952, Serial No. 21,889

Term of patent 14 years

(Cl. D52—1)

To all whom it may concern:

Be it known that I, James V. Grasso, a citizen of the United States, and a resident of Omaha, in the county of Douglas and State of Nebraska, have invented a new, original, and ornamental Design for a Radiator Flow Test Machine, of which the following is a specification, reference being had to the accompanying drawing forming a part thereof.

The figure is a front and side perspective view of a radiator flow test machine embodying my new design.

The rear and right side of the radiator flow test machine are substantially plain in appearance.

I claim:

The ornamental design for a radiator flow test machine, substantially as shown and described.

JAMES V. GRASSO.
